(57) **CLAIM**

The ornamental design for a shoe sole, as shown and described.

DESCRIPTION

FIG. 1 is a perspective view of a shoe sole, showing the design;

FIG. 2 is a front view of a shoe sole;

FIG. 3 is a rear view of a shoe sole;

FIG. 4 is a top view of a shoe sole;

FIG. 5 is a bottom view of a shoe sole;

FIG. 6 is a side view of a shoe sole; and,

FIG. 7 is a side view, opposite the side view shown in FIG. 6, of a shoe sole.

The dashed lines are included for the purpose of showing environmental structure and portions of the shoe sole that form no part of the claimed design.

1 Claim, 4 Drawing Sheets
